US0D1068708S

(12) **United States Design Patent** (10) **Patent No.:** **US D1,068,708 S**
(45) **Date of Patent:** **** Apr. 1, 2025**

(54) **ELECTRONIC DEVICE**

(71) Applicant: **Samsung Electronics Co., Ltd.**, Suwon-si (KR)

(72) Inventors: **Joo-Hyung Lee**, Suwon-si (KR); **Dawi Lee**, Suwon-si (KR)

(73) Assignee: **Samsung Electronics Co., Ltd.**, Suwon-si (KR)

(**) Term: **15 Years**

(21) Appl. No.: **29/895,260**

(22) Filed: **Jun. 20, 2023**

(30) **Foreign Application Priority Data**

Dec. 29, 2022 (KR) 30-2022-0055124

(51) **LOC (15) Cl.** **14-03**

(52) **U.S. Cl.**

USPC ..... **D14/138 G**

(58) **Field of Classification Search**

USPC ..... D14/130, 138 R, 138 AA, 138 AB, D14/138 AC, 138 AD, 138 C, 138 G, 341, D14/248

CPC ... H04M 1/0202; H04M 1/026; H04M 1/0264

See application file for complete search history.

(57) **CLAIM**

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depict portions of the electronic device which form no part of the claimed design.

1 Claim, 8 Drawing Sheets
